A. D. MUNSLAW

HOLDER CHECK AND EMERGENCY LOCK FOR HINGED DOORS AND WINDOWS

Filed Sept. 13. 1922

UNITED STATES PATENT OFFICE.

ARTHUR DAVIES MUNSLOW, OF POTTS POINT, NEAR SYDNEY, NEW SOUTH WALES,
AUSTRALIA.

HOLDER CHECK AND EMERGENCY LOCK FOR HINGED DOORS AND WINDOWS.

Application filed September 18, 1922. Serial No. 587,891.

To all whom it may concern:

Be it known that I, ARTHUR DAVIES MUNSLOW, a subject of the King of Great Britain and Ireland, residing at 20 Manning Street, Potts Point, near Sydney, New South Wales, Australia, have invented certain new and useful Improvements in Holder Checks and Emergency Locks for Hinged Doors and Windows, of which the following is a specification.

This invention relates to attachments for hinged doors and windows, for holding the same in fully open or partly open position and preventing rocking or rattling.

The device comprises a quadrant arm with a stub end for fixing it to a door or sash on or near the hanging stile, a bracket arm with a stub or flange for fixing it to the frame or architrave, a range of cup-holes and a range of through holes in the quadrant, and a spring pressed knuckle and a sprag pin carried on the end of said bracket and adapted to engage the quadrant cup-holes and through holes. The knuckle is housed in a cylinder on the bracket with an helical spring backing it and a screw down cap plate forming an abutment for the spring and providing a means for adjusting its tension. The knuckle bears frictionally on the quadrant and is engageable in the cup-holes therein, the spring being adjusted by means of the screw down cap to hold it sufficiently tightly to prevent accidental movement of the door or window sash by wind or by vibration. The sprag is inserted in one or other of the through holes in the quadrant to lock the quadrant to the frame bracket to fix the door or sash in any desired position at partial or full opening. As the attachment is not accessible from outside the door or window opening, the sprag attachment renders it efficient for holding doors and windows of ships' cabins, dressing rooms and other apartments partially open for purposes of ventilation whilst preserving privacy.

The device is illustrated in the accompanying drawings,—

- Fig. 1 being a top plan;
  - Fig. 2 an elevation, and
  - Fig. 3 a fragmentary vertical section.
- The quadrant 10 is fixed to the door or window 11 by a mounting stud flange 12. It is formed with a shallow groove 13 to

form a track for the knuckle, and at intervals along said groove with a series of cup depressions or holes 14 in which the knuckle may engage. A range of holes 15 is also formed in the quadrant to receive a sprag pin 16, which is freely hung to the bracket end by a chain. 17 is a bracket fixed to the frame 18 of the door or sash by a mounting flange 19. It carries a slot guide-way 20 for the quadrant 10 and above the guideway a pot or cylindrical housing 21 in which is an helical spring 22 which bears down on a foot disc 23 carrying a spherical knuckle 24 which protrudes through a hole in the pot bottom in register with the quadrant groove 13. The tension of the spring 22 is adjusted by means of a screw cap abutment 25. A wind 26 on the end of the bracket 17 is pierced with a hole 27 to accommodate the sprag pin 16.

The door or window is "bolted" in any required intermediate position by inserting the sprag pin 16 through one of the holes 15 and through the hole 27. When the sprag is not set, the knuckle acting on the sector imposes frictional resistance to the movement of the door or window according to the spring adjustment.

What I claim as my invention and desire to secure by Letters Patent is:—

1. A door or sash holder, comprising a flat bracket detachably mounted on the door frame, a cylindrical casing mounted on the free end of the bracket, said casing being provided with a horizontally disposed slot, a perforated false bottom in the casing and mounted above the slot, a ball projecting through said perforated bottom, a helical spring engaging said ball, means for adjusting the tension of the spring, and a flat quadrant plate mounted on the door and adapted to pass through the slot in the bracket, a longitudinal guiding groove for the spring pressed ball on the upper surface of said quadrant plate, said groove being provided with depressions at regular intervals along said groove.

2. A door or sash holder comprising a flat bracket mounted on the door frame, a cylindrical casing mounted on the free end of the bracket, said casing being provided with a horizontally disposed slot in the bottom thereof, a perforated false bottom mounted above the slot, a spring pressed

ball projecting through the perforation in the false bottom, a chain suspended pin attached to the free end of the bracket, and a flat quadrant plate mounted on the door and 5 adapted to be inserted into and slid within the slot in the bracket, said quadrant plate being provided on its upper face with a

longitudinal groove having depressions therein, the plate having holes disposed in the outer margin thereof to receive said 10 chain suspended pin.

In testimony whereof I affix my signature.

ARTHUR DAVIES MUNSLAW.
